L. Pomroy,
Casting Pipe

No 20,171.

Patented May 4, 1858.

UNITED STATES PATENT OFFICE.

C. POMROY, OF POTTSVILLE, PENNSYLVANIA.

IMPROVED CAST-IRON PIPE.

Specification forming part of Letters Patent No. 20,171, dated May 4, 1858.

To all whom it may concern:

Be it known that I, CLIFFORD POMROY, of Pottsville, in the county of Schuylkill and State of Pennsylvania, have invented a new and useful Improvement in Cast-Iron Pipes for Conveying Fluids, &c.; and I do hereby declare that the same is described and represented in the following specification and drawings.

To enable others skilled in the art to make and use my improvement, I will proceed to describe its construction and use, referring to the drawings, in which the same letters indicate like parts in each of the figures.

Figure 1 represents the drag or lower half of a flask containing the molding-sand and a section of a piece of pipe in the position in which it was cast. Fig. 2 is an elevation of one end of a flask with a metal core in it to chill the inside of the pipe cast around it. Fig. 3 is an elevation of the stand, lever, and weight used to hold the top section of the core in place in the flask.

The nature of my invention and improvement in cast-iron pipes for conveying fluids and other purposes consists in chilling the inside of such pipes by casting them on a metal core or in some other manner.

In the accompanying drawings, F is the top or cope of a flask, and F' the bottom or drag, both made of cast-iron from the same pattern, similar to many flasks used for casting pipe, such as is in common use, and particularly adapted to casting my improved pipe and chilling the inside by the use of a metal core, to which the flask is fitted by boring or reaming a hole in each end just large enough to fit the core to be used. This hole for the core is represented with a flange, C, around it in the drawings. Each portion of this flask is provided with flanges for the doweling-pins G G, which govern the position of the cope upon the drag and enable the workmen to put the cope on the drag with facility. There are four ears, E E, on the outer edges of the last-mentioned flanges, perforated for the bolts H H, which hold the cope and drag together while the pipe is cast. To make this core, I take one piece of iron (wrought or cast will answer) in the form shown at A, Fig. 2, and two pieces of the form shown at A' A', and of sufficient length to form the core, and fit their edges together by filing or planing, so as to

make a pretty close joint, making the top piece, A, from a sixteenth to an eighth of an inch wider at the bottom than the top, so that it can be easily pressed or forced in, so as to let the top edges of the pieces A' approach each other and yield to the cast-metal pipe as it shrinks around it in cooling, so as to prevent it from being cracked or otherwise injured as it cools and contracts. Besides, by making this piece A broader at the bottom than the top, or wedge-shaped, it can be readily dropped into the center between the pieces A A', and removed with facility, and also release the pieces A' A', so that they can be easily removed after the pipe cast around them has cooled. After the pieces A A' A' have been fitted to each other they may be clamped together and turned and filed or made smooth and of a proper size in some manner.

To hold the top piece, A, up in its place against the upper side of the hole in the flask and against the inside of the flange C, I make two small stands, like D, Fig. 3, and fit levers, like L, to each of them and weights B B to traverse on the levers, so that when the core is put into the flask the bottom of the stand D may be placed over the joint between the pieces A' A', as shown in Fig. 2, and the short end of the lever L brought up against the top piece, A, and the weight B adjusted to hold it in its place while the mold in the flask is filled with molten metal.

The flask and core having been prepared with the fixtures necessary to hold up the top piece of the core, a pattern may be made in the desired form for the outside of the pipe, with a core-print at each end of a proper size, or the same size as the metal core above mentioned, and long enough to reach into or through the holes in the ends of the flask, so as to form a place in the mold for the metal core, and also to hold the pattern in a proper position while the sand is rammed around it. For common pipe only one-half of a pattern will be necessary, as the cope and drag can each be molded or filled with sand on a flat board in the common or usual manner well known to molders, as the core-prints at the ends of the pattern hold it in the proper position when they are laid in the scores in the ends of the drag and cope, which form the holes for the metallic core around which the

pipe is to be cast. After the drag and cope have both been molded, by filling the space S, Fig. 1, with sand the pieces A' A' of the metal core may be laid into the scores in the end of the drag and the piece A laid between them, and the cope put on and secured to the drag by bolts or otherwise. The piece A may then be raised up into its place, and the stand and levers put in to hold it up, as shown in Fig. 1. The mold may now be filled with molten metal through proper gates formed in the mold. After the iron or metal begins to harden or set around the core and begins to shrink, if it does not force down the top piece of the core, the levers and weights should be raised and the top piece, A, driven down at each end, so as to let the pieces A A' be drawn toward each other at the top by the pipe as it shrinks around them in cooling, so as not to crack or injure it, and so that the core can be taken out with facility after it cools.

P is a longitudinal section of pipe cast around the metal core.

In order to prevent the molten metal as it is poured into the mold from melting and washing away a portion of the core, there should be two or a series of perpendicular gates made in the mold if the pipe is long, with a series of horizontal branches, one above another, leading from each of the perpendicular gates into the mold, the lower one entering the mold at the bottom, or in the mold for the flange on the end of the pipe, and the other branches in succession two or three inches apart, one above

the other, somewhat in proportion to the size and thickness of the pipe being cast, in a manner well known to foundry-men and molders.

It has been found that the water which accumulates in some of the mines in Pennsylvania is impregnated with something supposed to be sulphur or some of its acids, so that it dissolves or eats away common soft cast-iron pipes through which it is pumped, very fast, so as to render the pipe useless in a short time. It has also been ascertained that chilled cast-iron resists the action of such water, so as to be far more durable than unchilled or soft cast-iron; hence I have been induced to make cast-iron pipes and chill the inside, so as to resist the action of such water, and also to resist the action of the fine particles of coal carried in the water.

I believe I have described the process of making my improved cast-iron pipe, and represented the best apparatus known to me for making it, with directions for using the same. I will now state what I desire to secure by Letters Patent, to wit:

A cast-iron pipe chilled inside as a new article of manufacture, for the purpose of conveying fluids impregnated with or containing substances which soon destroy iron pipes which are not so chilled.

CLIFFORD POMROY.
